UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A COFFIN-PLATE.

SPECIFICATION forming part of Design No. 18,273, dated April 24, 1888.

Application filed January 3, 1888. Serial No. 259,749. Term of patent 14 years.

To all whom it may concern:

Be it known that I, OLIVER McCARTHY, of Meriden, in the county of New Haven and State of Connecticut, have invented a new Design for 5 Coffin-Plates; and I do hereby declare the following, when taken in connection with accompanying drawing, and the letters of reference marked thereon, to be a full, clear, and exact description of the same, and which said drawing 10 constitutes part of this specification, and represents a face view, the ornamentation omitted from one-half the surface.

This invention relates to a design for a plate for coffins and funeral purposes; and it consists in the representation upon a ground of 15 a bed or pillow of flowers, with a panel suitable for appropriate characteristics centrally disposed upon the plate.

In the accompanying illustration the surface 20 of the plate is represented as covered with

flowers, giving to the plate the appearance of a bed or pillow of flowers, and centrally disposed upon the surface is the representation of a panel suitable for appropriate characteristics, as shown in the accompanying illustration. 25

I claim—

The herein-described design for coffin-plate, the surface represented as covered with flowers and leaves, giving to the plate the appearance of a pillow of flowers, and also the representation of a panel suitable for appropriate characteristics centrally disposed on the surface, as described, and shown in the accompanying illustration. 30
